UNITED STATES PATENT OFFICE.

ERNEST E. HILLS, OF MEDINA, WISCONSIN.

SHOE-FASTENER.

1,277,417.

Specification of Letters Patent.

Patented Sept. 3, 1918.

Application filed December 15, 1917. Serial No. 207,253.

To all whom it may concern:

Be it known that I, ERNEST E. HILLS, a citizen of the United States, and a resident of Medina, in the county of Outagamie and 5 State of Wisconsin, have invented certain new and useful Improvements in Shoe-Fasteners, of which the following is a specification.

My invention is an improvement in shoe 10 fasteners, and has for its object to provide a fastener of the character specified for connecting the flaps of a shoe, which will simulate the usual lacing, and wherein a series of clasps is provided for each flap, each 15 clasp consisting of a substantially U-shaped member or yoke comprising a body and arms, the arms of each yoke having eyelets for engaging the eyes of the flap, and the bodies of the yokes having interengaging 20 means for connecting said yokes.

In the drawings:

Figure 1 is a perspective view of a shoe showing the fastener in use;

Fig. 2 is a perspective view of a clasp of 25 one series;

Fig. 3 is a similar view of a clasp of the other series;

Fig. 4 is a cross-section through the united 30 clasps shown in Fig. 1.

The present embodiment of the invention is shown in connection with the flaps 1 and 2 of a shoe 3, the clasps being connected with the eyelets 4 of the flaps.

The clasps are arranged in two series, one 35 series being connected with each flap, and the clasps 5 and 6 of the series are substantially U-shaped members or yokes, each comprising a body and arms extending at approximately a right angle from the body.

The arms of each yoke have eyelets 7 for 40 engaging the eyes 4 of the flaps, and these eyelets are adapted to be upset in the usual manner to permanently connect the clasps with the flaps.

The body of the clasp 6 has a bead 8,

formed by rolling an extension from the body upon itself, and the body of each clasp 5 has a hook 9 for engagement by the bead of the adjacent clasp 6.

In use, the flaps of the shoes are provided 50 with the clasps, and when it is desired to connect the flaps, the beads 8 of the clasps 6 are engaged with the hooks 9 of the clasps 5. When the shoe is completely laced, the arms of the clasps will simulate the laces, 55 and the interengaging mechanism between the series of clasps will be a line at the center of the space between the flaps. While permitting the quick attachment and detachment of the flaps, the fastener very closely 60 resembles the usual lacing.

I claim:

1. In combination with a shoe, a fastener for the flaps, said fastener comprising a series of clasps for each flap, each clasp being 65 a yoke comprising a body and arms extending at approximately right angles to the body, the arms having eyelets for engaging the eyes of the flaps and the bodies having interengaging means for connecting the series, the bodies of one series having beads 70 and the bodies of the other series having hooks for engaging the beads, said beads and hooks extending approximately the full length of the body. 75

2. A fastener for shoe flaps, comprising a series of clasps for each flap, each clasp being yoke shaped and comprising a body and arms extending at approximately right angles to the body, the bodies of the clasps 80 of one series having beads and the bodies of the clasps of the other series having hooks for engaging the beads, the beads and hooks of the clasps extending the full length of the bodies, and the hooks being open and un- 85 obstructed at the ends of the body.

ERNEST E. HILLS.
